BEDSPRING CONSTRUCTION

Solomon Raduns, Brooklyn, N. Y., assignor to
Greenpoint Metallic Bed Company, Inc., Brook-
lyn, N. Y.

Application April 25, 1938, Serial No. 204,018

4 Claims. (Cl. 5—252)

The present invention relates to an improved spring construction particularly designed to be utilized in beds.

It is among the objects of the present invention to provide an inexpensive bedspring construction which will be durable, comfortable and will be balanced against distortion in any direction, even though the spring be unevenly loaded at different parts thereof.

10 Another object is to provide a bedspring with an improved stabilized construction which will eliminate lateral displacement of the upper portion of the spring without causing undue stress upon the lower spring structure and without twisting or disarrangement tending to break or rupture or cause damage to the spring construction as a whole, even though the spring be substantially unbalanced in its loading.

15 Other objects will be obvious or will appear 20 during the course of the following specification.

In accomplishing the above objects it has been found most satisfactory to provide a relatively rigid lower frame of substantial strength with cross braces to support the bottom of the main 25 vertical coil springs. The centrally positioned main coil springs are preferably provided with a lattice-like platform or frame which is clamped between the closed coils thereof. This platform is preferably connected by elongated small 30 diameter coil springs to the bottoms or lower portions of the peripheral main vertical coil springs. The upper frame is more rigid than the center intermediate frame, but less rigid than the bottom frame.

35 To the upper frame are connected the outside edges of the top coils or rungs of the main coil springs, the top rungs preferably being in the plane of the upper frame.

40 The top or upper frame is preferably stabilized against the lateral displacement by a plurality of downwardly and inwardly inclined stabilizer bar elements which have a four-point diagonal resilient suspension substantially in the plane of the lowermost frame.

45 In the preferred construction, the lowermost end of the inclined stabilizer is bent into a horizontal plane and is positioned in the plane of the lowermost frame. This bent end is connected by four diagonally extending coil springs to the lower rung or coil of the intermediate main coil springs.

50 In the drawings which illustrate one of the various possible embodiments according to the present invention, but to which the present

invention is by no means restricted, since many variations, alterations and modifications might all be made within the spirit and scope thereof:

Fig. 1 is a top plan view of the spring construction with the spring being considerably shortened longitudinally and laterally to enable a more compact showing.

Fig. 2 is a side sectional view upon the line 2—2 of Fig. 1.

Fig. 3 is a fragmentary bottom view upon the line 3—3 of Fig. 2.

Fig. 4 is a transverse sectional view upon the line 4—4 of Fig. 1 taken through the longitudinal axis of the spring.

Referring to the drawings, the spring consists of a lower or bottom rigid frame A, a less rigid upper or top frame B and an intermediate strip metal lattice frame or platform C. The main large diameter vertical coil springs D connect these frames and support the upper frame B and the intermediate frame C from the lower frame A.

The stabilizers E are connected between the upper frame B and the lower frame A. The stabilizers E are resiliently attached to the bottoms of the main coil springs D and they prevent lateral displacement of the upper frame B.

The lower frame A consists of a rectangular bar element 10 of angular cross section, as best shown in Figs. 2 and 4. The bar 10 is riveted at 13 by the vertical flanges 11 to the upturned ends 15 of the cross members 12. The cross members 12 are bent horizontally at 14 adjacent the frame 10.

The intermediate portions 16 of the cross members 12 are twisted at 17 into a vertical plane, and these vertical portions 16 at 18 receive and are connected to the lowermost rungs or coils 19 of the intermediate coil springs D. The lower rungs 20 of the peripheral coil springs F rest upon the horizontal portions 14 of said cross members 12.

The upper portions of the vertical cross member 16 are also recessed at 21 (see Fig. 4) to receive the upturned portions 22 of the crossing wires 23. These wires 23 are substantially in the plane of the lower frame A and they are attached at their looped end portions 24 to the vertical flange 11 of the rectangular element 10.

The wires 23 support the peripheral coil springs F, along the end by the upturned portions 25 projecting inside of the lowermost coils 26, as shown in Fig. 4. Between the lowermost coil 26 and the upturned loop 25 along the short sides of

the frame A extend the transverse wires 27 to form a permanent connection. The transverse wires 27 are connected at the ends of the structure A to the vertical flanges 11 by loops (not shown) which are similar to those indicated at 24 in Fig. 4.

10 The longitudinal wires 28 along the long sides of the frames A, as best shown in Figs. 2 and 3, have down-turned loops 29, which extend below the horizontal portions 14 of the cross members 12 and engage the edges thereof. The wires 28 on each side of the loops 29 extend over the lower rungs 20 of the peripheral main springs F and lock them in position upon said cross members 12.

15 The middle coils 30 of the main coil springs D are brought closer together so as to clamp the intermediate lattice frame C in position. The lattice frame is formed of the crossing strips 31 and 32, the strips 31 having elevated portions 33 to receive the longitudinal elements 31 inside of the closed coils 30 of the intermediate springs D.

20 The ends of the strips 31 and 32 are respectively connected by means of the downwardly extending elongated small diameter coil springs 34 and 35 to the lower rungs or coils 36 and 37 adjacent to, but removed from, the lowermost rungs of the peripheral springs F.

25 30 By including the springs 34 and 35 extending downwardly from the intermediate lattice platform C, it has been found that the lower portion of the bedspring is stabilized and will most readily resist the downwardly applied deforming stresses without loss of comfort, with the upper portion of the bedspring above the lattice C being under relatively less tension than the lower portion below the lattice C. Moreover the load upon the stabilizers E is considerably lessened.

35 40 The upper frame B consists of a rectangular ring 38 less rigid than the bottom frame B. The rectangular ring 38 is tied at 39 to the sides or edges of the uppermost coils 40 of the peripheral coil springs F, preferably at points at least 90° away from the points 41 where the springs F are tied together at their uppermost rungs or coils. The top coils 40 of said coil springs B are connected to the intermediate springs D by the crossing diagonal springs 42, which are connected or interlaced together at 43. It will be noted 45 50 that the peripheral coil springs F are devoid of direct connection to each other, while the various intermediate springs D are not only connected to each other by the crossing diagonals 42, but are also connected to the peripheral springs F.

55 It will be noted by referring to Fig. 1 that the bottom frame by reason of the cross beams 12 and the cross wires 27 and 28 will form a series of squares, which coincide with the squares formed by the intermediate lattice C.

60 It has been found that to obtain maximum stabilization, the lower horizontally-bent ends 44 of the stabilizers E should be centrally located in said squares 45 removed from the frame A by the distance of about one or two squares 45. The lower flattened ends 44 are preferably provided with the holes 46 which receive the inner ends of the coil springs 47, which at their exterior ends are connected to the lowermost rungs 18 of the intermediate coil springs D.

65 70 The stabilizers E as shown have vertically extending portions 48, diagonal extending portions 49 and they terminate in a loop 50 which may be rigidly or pivotally connected to the frame B.

75 75 Many other changes could be effected in the

particular features of bedspring construction designed, and in methods of operation set forth, and in specific details thereof, without substantially departing from the invention intended to be defined in the claims, the specific description herein merely serving to illustrate certain elements by which, in one embodiment, the spirit of the invention may be effectuated.

What is claimed is:

1. A bedspring construction comprising a relatively rigid rectangular lower frame, a relatively rigid rectangular upper frame, a plurality of main vertical coil springs of increasing diameter upwardly extending between said lower frame and said upper frame connected to and supported at their lower ends by the lower frame and in turn connected to and supporting the upper frame at their upper ends, an intermediate frame positioned between said upper frame and said lower frame and attached to the middle portions of said main coil springs, and an obliquely downwardly extending stabilizer bar resiliently connected by four diagonally disposed short horizontally positioned coil springs to the bottoms of four of said coil springs and directly connected to the upper frame.

2. A bedspring construction comprising an upper frame, a lower frame, a plurality of main vertical coil springs extending between said upper frame and said lower frame connected at their upper ends to said upper frame, a lattice work in the plane of and connected to said lower frame supporting the bottoms of said coil springs, said lattice work forming a plurality of squares and downwardly inclined stabilizer elements attached at their upper ends to the upper frame and positioned at their lower ends in the middle of the squares of said lattice, the lower ends of said stabilizer bars being resiliently connected to the lower turns of said coil springs at the corners of said respective squares by short diagonally extending coil springs.

3. A bedspring construction including an upper frame, a lower frame and stabilizer constructions comprising obliquely downwardly extending bars directly connected to said upper frame at their upper ends and extending to the plane of said lower frame, and a plurality of said vertical coil springs between said upper and lower frames connected to and supported at their lower ends by the lower frame and in turn connected to and supporting the upper frame at their upper ends, and means resiliently connecting said bars to the lower frame, the means connecting said bars including four diagonally disposed short horizontally positioned coil springs connected to lower turns of four adjacent main coil springs.

4. In a bedspring construction of the type having an upper frame and a lower frame and a plurality of main vertical coil springs connected to and supported at their lower ends by the lower frame and in turn connected to and supporting the upper frame at their upper ends, an oblique stabilizer bar construction extending between said upper frame and said lower frame, said coil springs being arranged in rows and said bar extending beyond two successive rows of said main springs and being supported between the second and third rows from its point of attachment to the frame by four diagonally disposed short horizontally positioned short coil springs connected to lower turns of four adjacent main coil springs.
